(57) **CLAIM**

The ornamental design for a display screen or portion thereof with graphical user interface, as shown and described.

DESCRIPTION

FIG. 1 is a front view of a display screen or a portion thereof with a graphical user interface.

FIG. 2 is a front view of a second embodiment thereof; and, FIG. 3 is a front view of a third embodiment thereof. The dash-dot-dash broken lines shown on the graphical user interface form no part of the claimed design.

In all of the figures, the outermost broken lines forming a dash-dot-dash line pattern show a display screen or a portion thereof, and form no part of the claimed design.
